United States Patent Office

Des. 227,545
Patented July 3, 1973

227,545

SIDE SHEAR BLADE

Kunio A. Sumida, Los Angeles, Calif., assignor to
Leonard U. Shapiro, St. Paul, Minn.

Filed July 21, 1971, Ser. No. 164,979

Term of patent 14 years

Int. Cl. D8—99

U.S. Cl. D8—98

FIG. 1 is a perspective view of a side shear blade illustrating a new design therefor;

FIG. 2 is a top plan view thereof;

FIG. 3 is a side elevation view of the side shear blade taken from the side opposite FIG. 1;

FIG. 4 is a bottom plan view thereof; and

FIG. 5 is a front elevation thereof.

I claim:

The ornamental design for a side shear blade, substantially as shown.
